UNITED STATES PATENT OFFICE.

ARTHUR E. DANKE, OF NEENAH, WISCONSIN, ASSIGNOR OF ONE-HALF TO JOHN F. STROEBEL, OF NEENAH, WISCONSIN.

CONVEYER.

1,312,166.

Specification of Letters Patent. Patented Aug. 5, 1919.

Application filed January 11, 1918. Serial No. 211,340.

To all whom it may concern:

Be it known that I, ARTHUR E. DANKE, a citizen of the United States of America, residing at Neenah, in the county of Winnebago and State of Wisconsin, have invented certain new and useful Improvements in Conveyers, of which the following is a specification, reference being had therein to the accompanying drawing.

10 The invention relates to conveyers and more particularly to a device for engaging, lifting, conveying and dumping a receptacle of the construction described and illustrated in my copending application having the 15 Serial Number 211,341 and filed under even date.

The pan forming the subject matter of the application for Letters Patent above referred to may be briefly described as being of ob- 20 long form adapted to be inserted in a gutter and provided with trunnions at the ends to afford engagement points when the pan is to be conveyed.

It is an object of the invention to provide 25 a device capable of elevating the pan without the gutter in which it is normally received, and conveying the same to a desired place for the purpose of discharging the contents of said pan.

30 A further object constitutes the provision of a conveyer which may be adjusted to suit different lengths of pans.

It is also an object of the invention to provide a conveyer equipped with means for automatically tilting the carried receptacle 35 into discharging position.

A further object aims at the provision of means for restoring the tilting into normal position after discharge of the receptacle 40 has been effected.

Still another object embraces the provision of automatically acting restoring means whereby the parts of the conveyer are set for a successive operation.

45 To the accomplishment of the foregoing and related ends, the invention, then, consists of the means hereinafter fully described and particularly pointed out in the claims, the annexed drawings and the following description setting forth in detail certain mechanism embodying the invention which, however, constitute but several of the various ways in which the principle of the

invention may be used. In the annexed drawing:

55 Figure 1 is a side elevation of a conveyer constructed in accordance with the invention and carrying the receptacle in normal position.

Fig. 2 is a similar view with the receptacle 60 in discharging position.

Referring to the drawing, 1 designates a track provided in a barn at suitable distance from the floor and supported in overhead position in any preferred or suitable 65 manner, care being taken that the track does not interfere with accessibility of the barn. The track 1 extends out of the barn to a point where the discharge of the receptacle carried by the same is desired.

70 A carriage generally designated by 2 comprises a frame 3 equipped with arms 4 to which rollers 5 are secured running on the track 1 and thus supporting the carriage, the latter may be of any construction and pref- 75 erably is of standard design as obtainable on the open market. The carriage frame is equipped with a shaft 6 journaled therein and having gear wheels 7 adjacent the ends.

A shaft 8 is journaled in depending brackets 9 of the frame and carries pinions 10 in mesh with the pinions 7. A chain 11 is fastened to an ear 12 of the bracket 9 and is wound in a plurality of convolutions on the shaft 6 and has its end secured thereto for a 80 purpose hereinafter specified. A similar chain 13 is connected to the frame 3 and likewise arranged on the shaft 6. The shaft 8 carries a pulley 14 at its right end, as viewed in Fig. 1, about which a chain 15 is 85 trained so that by manipulation of the same the chains 11, 13 may be wound upon or unwound from the shaft 6 as will be obvious.

The parts heretofore described are common to devices of this character and no 90 claim is made thereto. As indicated in the drawing the chains 11, 13, form holding means for a frame generally designated by 16 and which might be termed the carrier for the receptacle. The frame 16 includes a 100 tubular member 17 having teeth 18 at its ends. The member 17 receives rods 19, 20, which telescope therein to provide for adjustability of the carrier in conformity with the length of a particular receptacle to be 105 carried. Each of the rods 18, 19 is provided

with a hanger bar 21 terminating at the lower extremity into a hook 22 adapted to seize a trunnion of the receptacle 23 shown in dotted lines. At the upper end each hanger 5 bar 20 is provided with a hook 23' pivotally connected thereto and adapted to engage one of the teeth 18 in order to lock the rods 19, 20 in adjusted position. Intermediate its ends the member 17 is provided 10 with a depending bracket 24 to which an arm 26 is secured by a pivot pin 25. The arm 26 is slotted as at 27 to receive the free end of a spring member 28 secured to the bracket 24 whereby the arm 26 is normally 15 held in vertical position.

Equally spaced from the pivot pin 25 hook members 29 are arranged on the arm 26 to engage the free ends of connecting rods 30 secured at the opposite ends to the links 20 31 pivoted intermediate their ends at 32 to the hanger bars 21. The links 31 engage with their lower end the receptacle carried by the frame 16 so as to prevent tilting of the receptacle during conveyance. 25 The member 17 is provided with rollers 32 around which the chains 11, 13 are trained.

The device is used in the following manner. The carrier is adjusted to a particular pan by adjusting the rods 19, 20 and locking 30 the rods in adjusted position by means of the hooks 23. The bars 21 are then hooked to the trunnions of the pan and the carrier frame 16 together with the pan 23 is raised by manipulation of the chain and 35 is moved on the track 1 outside of the barn. During this movement the arm 26 is in vertical position and consequently the lower ends of the links 31 engage the receptacle 23. Near the end of the track a pin 33 is provided thereon forming an abutment for the 40 arm 26 which is tilted. Incidentally the links 31 are forced to release the pan 23 and the latter then is free to swing into discharging position.

45 In the drawing the preferred embodiment of the invention is shown, but numerous modifications and changes may be applied without departing from the scope of the invention. I therefore, do not limit myself to 50 the exact details as shown but desire to avail myself of any departures falling within the scope of the invention as indicated in the appended claims.

I claim:

55 1. A pan carrier comprising in combination with a carriage, a tubular member adjustably suspended therefrom, a pair of holding arms slidably arranged in said member, said member being formed with teeth, 60 means provided on said arms and adapted

to engage said teeth for locking said arms in adjusted position, means for locking the pan carried by said arms against movement, and adjustable means for automatically releasing said locking means. 65

2. A pan carrier comprising in combination with a carriage, a tubular member adjustably suspended therefrom, a pair of holding arms slidably arranged in said member, means for locking said arms in adjusted position, links pivotally connected to said arms for locking the pan carried by said arms against movement and means for automatically releasing said links, said releasing means comprising rods connected to said 75 links, and an arm adjustably connected to said rod.

3. A pan carrier comprising in combination with a carriage, a tubular member adjustably suspended therefrom, a pair of holding arms adjustably arranged on said member, means for locking said arms in adjusted position, links pivotally connected to said arms and adapted to bear against the pan carried by the arms, a tilttable arm arranged between said links, rods interconnecting said links and said tilttable arm, and means for normally holding said tilttable arm in inoperative position. 85

4. A pan carrier comprising in combination with a carriage, a tubular member adjustably suspended therefrom, a pair of holding arms adjustably arranged on said member, means for locking said arms in adjusted position, links pivotally connected to said arms and adapted to hold the pan carried by said arms against movement, a lever arranged between said links, adjustable connections between said links and lever, and a spring opposing movement of said lever. 90

5. A pan carrier comprising in combination with a carriage a tubular member adjustably suspended therefrom and being provided with teeth, a pair of holding arms adjustably arranged on said member, hook members articulated with said arms and adapted to engage said teeth, links pivotally connected to said arms and adapted to hold the pan carried by the same against movement, a lever having a slot arranged between said links, adjustable connections between said links and lever to transmit motions of said lever to said links, and a leaf spring secured to said member and entering the slot in said lever to normally hold the same in inoperative position. 105 110 115

In testimony whereof I hereunto affix my signature.

ARTHUR E. DANKE.
